UNITED STATES PATENT OFFICE.

MICHAEL WASCHBUSCH, OF PARK RIDGE, ILLINOIS.

PLAYHOUSE.

Application filed October 19, 1925. Serial No. 63,245.

My invention relates to play houses and the same has for its paramount object the provision of an improved play house construction which will embody certain desired features of simplicity, efficiency and convenience, and which will be extremely economical in manufacture and durable in use. A further object is the provision of a simplified construction which may be used in general in the manufacture of toy houses, bird houses and the like.

Other objects will appear hereinafter.

The invention consists in the combinations and arrangements hereinafter described and claimed.

The invention will be best understood by reference to the accompanying drawings, forming a part of this specification, and in which,

Fig. 1 represents a front elevational view of a toy house made in accordance with the present invention;

Fig. 2 is an end view thereof;

Fig. 3 is a fragmental horizontal sectional view through the walls of the play house;

Fig. 4 is a fragmental vertical sectional view through the walls and flooring of the same;

Fig. 5 is a sectional view taken substantially on the line 5—5 of Figure 6 showing the clip means for securing the walls together;

Fig. 6 is a fragmentary view of a corner in elevation, with the roof applied thereto;

Fig. 7 is a fragmental sectional view showing the window framing incorporated in a side wall;

Fig. 8 is a similar view but showing a door substituted for the window; and

Fig. 9 is a fragmentary view of an end wall and the roof, these parts being separated but in proper relative position and embodying the means whereby the roof is held in position upon the end wall.

The preferred embodiment of my invention, as illustrated in the accompanying drawings, comprises a base part 10 in the form of a suitable board or flooring, opposed side walls 11 and opposed end walls 12, constructed and proportioned for mounting upon the flooring 10. The side and end walls 11 and 12 are preferably made of concrete reenforced by suitable wire mesh 13; and the same are also produced with reenforcing rods 14 adjacent their corner edges; which rods protrude for a distance below

their lower edges as shown. For the reception of the protruding ends of the rods 14, the flooring 10 is provided with apertures 14'. By this arrangement, the side and end walls 11 and 12 are detachably secured in position upon the flooring 10.

Means are provided for securing the side and end walls together at their top corners; and this means consists in providing the top and end walls with notches 15, produced from their top or roof edges in proximity to the meeting edges at the corners. Adapted to be removably disposed within adjacent corner notches 15 are corner-shaped clip members 16, which embrace the corners and secure together in tight relation the corner producing walls. The side and end walls, thus held to the flooring 10 by the rods 14, and thus secured to each other by the corner clips 16, provide a practical and efficient construction; and additionally the parts comprising the structure so produced, may be readily separated for purposes of transportation, storage, or removal from one place to another.

Preferably and as shown, the end walls 12 of the structure are each formed at their top ends with oppositely sloping edges for the accommodation thereon of oppositely sloping roof sections 17. In order to maintain the roof sections 17 in position upon the sloping top edges of the end walls 12, the said roof sections are each provided with depending tenons 18 adapted to seat in correspondingly formed notches 19 provided for the purpose in the sloping top edges of the end members 12. The roof sections 17 not only rest upon the end walls 12 but also upon the side walls 11 from which they overhang in the customary manner.

The side and end walls 11 and 12 may, if desired, be produced with window framing members incorporated therein. The framing members consist of U-shaped parts 20, adapted when the concrete is poured in the usual mould, to receive the concrete between their flanges 21 whereby the U-shaped sections will be firmly held by the concrete thus received therein. U-shaped framing members 20 are thus provided for the sides and ends of the windows. To the framing members 20 are secured strips 22 provided with shoulders 23 throughout their lengths. The said strips 22, with their shoulders 23, comprise the means whereby to retain either the usual window sash 24 (Figs. 1 and 2) or a

window pane 25 (Fig. 7). In Fig. 8 I have illustrated a door 26 applied to the framing members 22 and abutting against the shoulders 23 thereof.

5 While I have illustrated and described the preferred form of construction for carrying my invention into effect, this is capable of variation and modification without departing from the spirit of the invention. 10 I, therefore, do not wish to be limited to the precise details of construction set forth, but desire to avail myself of such variations and modifications as come within the scope of the appended claims.

15 Having described my invention, what I claim as new and desire to secure by Letters Patent is:

20 1. A house structure of the kind set forth comprising a floor part; separable side and end walls mounted upon the floor part and having means interlocking therewith; corner clips separably connecting the side and end walls; and a roof removably arranged upon the side and end walls, substantially 25 as described.

2. A house structure of the kind set forth comprising a floor part; side and end walls arranged to be removably supported thereon made of reenforced concrete; said walls provided with window and door framing consisting each of channeled sections held by the concrete received therein; means for removably securing said side and end walls in position and a roof removably arranged 35 thereon, substantially as described.

3. A house structure of the kind set forth comprising a floor part having apertures therein; side and end walls arranged to be removably supported upon the floor part; rods protruding from said walls and removably enterable in said apertures; and means for releasably securing said side and end walls together comprising notches provided therein and clip members shaped to embrace the corners enterable in said notches.

4. A house structure of the kind set forth comprising a unitary floor part having apertures therein; unitary side and end walls

arranged to be removably supported upon said floor part; rods protruding from said walls and enterable in said apertures, means for releasably securing said side and end walls together comprising notches provided in the top ends thereof and clip members shaped to embrace the corners and engaged in said notches; and a unitary roof adapted to be removably supported upon said walls and provided with depending tenons, said end walls having notches therein for the reception of said tenons by which to hold the roof in position, substantially as described.

5. A house structure of the kind set forth comprising a unitary floor part; unitary side and end walls mounted upon said floor part and having means interlocking therewith; corner clips connecting said side and end walls; and a unitary roof supported upon said side and end walls, substantially as described.

6. A house structure of the kind set forth comprising a unitary floor part; unitary side and end walls arranged to be supported thereon, made of re-inforced concrete; said walls provided with window and door framing consisting each of channeled sections held by the concrete received therein; means for securing said side and end walls in position and a unitary roof supported thereon, substantially as described.

7. A house structure of the kind set forth comprising a unitary floor part having apertures therein; unitary side and end walls arranged to be supported upon said floor part; rods protruding from said walls and enterable in said apertures; means for securing said side and end walls together, comprising notches provided therein and clip members shaped to embrace the corners enterable in said notches; and a unitary roof part arranged to be supported on said side and end walls, substantially as described.

In testimony whereof I have signed my name to this specification.

MICHAEL WASCHBUSCH.
